FIG. 4.

FIG. 3.

UNITED STATES PATENT OFFICE.

CHARLES C. HOCKINS, OF ROCHESTER, NEW YORK.

HUMIDIFIER.

Application filed July 8, 1922. Serial No. 573,640.

To all whom it may concern:

Be it known that I, CHARLES C. HOCKINS, a citizen of the United States, residing at Rochester, in the county of Monroe and State of New York, have invented new and useful Improvements in Humidifiers, of which the following is a specification.

This invention relates to means for moistening the air in a room or building, the general object of the invention being to provide means for producing steam and for introducing the steam into the room directly or to the hot air space of the furnace.

Another object of the invention is to provide means for heating the water by the products of combustion from the heating system.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a view of the invention in use showing parts in section.

Figure 2 is an enlarged longitudinal sectional view through the water heater.

Figures 3 and 4 are views of a modification.

In these views 1 indicates a drum which contains a tank 2, said tank being spaced from the inner walls of the drum, as shown. This drum is provided with an inlet 3 which is connected with the smoke pipe 4 of the furnace 5 and with an outlet 6 which leads to the chimney 8. Thus the products of combustion from the furnace will circulate within the space between the drum and tank so as to heat the water in the tank and produce steam. This steam is led from the upper part of the tank by a pipe 9 which may lead the steam into the hot air space of the furnace, as shown in Figure 1, and thence the steam will moisten the hot air and such moistened hot air will be dis-

charged throughout the building through the medium of the hot air conductors 5' or this pipe may lead the steam directly into the room or building, as shown in Figure 3. When led into the hot air space of the furnace the steam will moisten the air therein before this air passes into the room or rooms to be heated. When led directly into the room or rooms the moistening effect will be increased. Water may be supplied to the tank in any desired manner, though I prefer to provide a tank 10 which is suspended from the ceiling and is connected by the pipe 11 with a main supply. A pipe 12 connects the tank 10 with the tank 2. This pipe may be provided with a valve 13 for controlling the flow of water from the tank 10 into tank 2.

I may also provide automatic means for controlling the level of water in tank 2. Such means consists in making the tank 2' movable, as shown in Figure 3, suitable packing material being placed between the top of the drum 1 and said tank to prevent the escape of smoke from the drum. The tank 2' is suspended from a pivoted lever 14 which has a weight 15 thereon for counter-balancing the tank 2' and its contents. Both the inlet pipe and the outlet pipe for the steam are provided with telescoping portions, as shown at 16, for permitting movement of the tank relative to the pipes. The parts are so arranged that when the tank 2' has its water level too low the weight 15 will overbalance the tank, thus raising the tank and opening the valve 16 to permit a quantity of water to flow into the tank. As soon as sufficient water has entered the tank the tank will move to its normal position and thus close the valve.

This device will moisten the air in a building or room, which, as is well known, aids in maintaining the health of the occupants.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a furnace having the usual smoke pipe, of a drum arranged intermediate the ends of the smoke pipe and in communication therewith, a water tank entering the drum and spaced from the wall thereof so that the products of combustion

from the furnace will heat the water in the tank, valved means for supplying water to the tank, and means for conveying steam 10 from the tank to moisten the air from the furnace.

In testimony whereof I affix my signature.
CHARLES C. HOCKINS.
